UNITED STATES PATENT OFFICE

2,628,145

EXPANSIBLE CABINET

Edward J. Slattery, Montgomery County, Md.

Application November 28, 1947, Serial No. 788,766.

1: Claim. (Cl. 312—205)

1 My invention consists in a new and useful improvement in cabinets and is designed to provide a cabinet having a combination of a plurality of compartments and a plurality of tables, intended more particularly for reception of sound record discs and albums containing same. The particularly novel and useful features of my improved cabinet are the combination of a pair of centrally disposed superposed compartments of constant volume, the lower one of which is open at its front and the upper being closed at its front by a hinged door, and a pair of adjustable lateral compartments, the volumes of which may be independently varied, the cover of the upper central compartment constituting a table of constant area and the covers of the lateral compartments constituting tables of variable areas, and the novel means whereby the lateral compartments may be adjusted.

2 While I have illustrated in the drawings and have hereinafter fully described one specific embodiment of my invention, it is to be distinctly understood that I do not consider my invention to be limited to said specific embodiment but refer for its scope to the claim appended hereto.

In the drawings:

Fig. 1 is a perspective view of the cabinet, the upper compartment being closed, the lateral compartments being in extended position and a portion of the lower compartment being broken away to disclose its interior construction.

Fig. 2 is a perspective view of the cabinet, the upper compartment being open, the lateral compartments being in retracted position and a portion of the lower compartment being broken away to disclose the parts of the interior construction which have been moved from their positions as shown in Fig. 1, by retraction of the lateral compartments.

Fig. 3 is an enlarged vertical section on the line 3—3 of Fig. 4, in the direction of the arrows.

Fig. 4 is an enlarged vertical section on the line 4—4 of Fig. 3, in the direction of the arrows.

Fig. 5 is a greatly enlarged fragmentary perspective view of one of the improved ball rollers for the lateral compartments with its mounting and one of the guide keys and its key-way for the lateral compartment.

Fig. 6 is a greatly enlarged vertical section on the line 6—6 of Fig. 4, in the direction of the arrows, of one of the ball rollers, its mounting and the track in which it is received.

Fig. 7 is a greatly enlarged fragmentary vertical section of one of the supporting rollers on the bottom of the outer ends of the lateral compartments.

Fig. 8 is an enlarged vertical section on the line 8—8 of Fig. 3, in the direction of the arrows. As illustrated in the drawings, my improved cabinet has an upper central compartment A, with a drawer B, a lower central compartment C, and lateral compartments D and E.

The cabinet has a top panel 1 mounted on side panels 2 and 3 in which are mounted a bottom panel 4 and an upper intermediate panel 5. The top panel 1, upper portions of side panels 2 and 3 and the intermediate panel 5 comprehend the upper compartment A. Suitably spaced above the bottom panel 4 there is a lower intermediate panel 6 mounted in the side panels 2 and 3. The upper intermediate panel 5, lower portions of the side panels 2 and 3 and the lower intermediate panel 6 comprehend the lower compartment C.

A front panel 7 beneath the lower intermediate panel 6 extends between the side panels 2 and 3. A cleat 8 on the bottom panel 4 is parallel with the side panels 2 and 3 and midway therebetween, for a purpose presently explained. A second cleat (not shown) is similarly mounted on the upper intermediate panel 5.

25 The means for slidably mounting the drawer B are shown in Figs. 2, 3, 4 and 8; the drawer B being omitted in Figs. 3 and 4 for clarity. Suitably mounted on the side panels 2 and 3 there are tracks 9. Tracks 10 are mounted on the sides of the drawer B. Ball races 11 interposed between the tracks 9 and 10 carry ball bearings 12 freely rotatable between the opposed concave surfaces 13 and 14 of the tracks 9 and 10, respectively. A bumper 15 on the forward end of each track 9 and a bumper 15-a on the rear end of each track 10 limit the outward movement of the drawer B, and a bumper 15-b on the rear end of each of the tracks 9 limits the inward movement of the drawer B.

40 Since the lateral compartments D and E have identical structural elements and differ only in their positions (left and right) in the cabinet (Fig. 1) a description of the structural elements of one of said lateral compartments will suffice.

45 Each of the side panels 2 and 3 is provided with a suitably disposed and configured orifice 16 immediately above the upper surface of the upper intermediate panel 5, and an identical orifice 17 immediately below the intermediate panel 6 and the bottom panel 4 (Fig. 4). Each lateral compartment has a top panel 18 and a bottom panel 19, slidably in the orifices 16 and 17 respectively, and connected at their outer ends by an end panel 20. Suitably key-ways 21 are counter-sunk in the upper intermediate panel 5 and the bottom panel 4, and the top and bottom panels 18

and 19 are provided with keys 22 slidable in said key-ways 21 (Figs. 3, 4 and 5).

Suitably mounted on the rear and forward portions of the upper intermediate panel 5 there is a pair of struts 23 extending between the side panels 2 and 3 and spaced slightly from the sides of the top panels 18. Each strut 23 has counter-sunk in its edge adjacent the side of a panel 18 a track 24 (U-shaped in cross-section). Each panel 18 is provided on its inner end with a plate 25 from the ends of which project pins 26 loosely received in bores 27 in ball rollers 28 rollably mounted in the tracks 24. It will be noted (Fig. 6) that the parts are so designed and related that the panels 18 are supported by the balls 28 resting on the lower horizontal portions 24-a of the tracks 24 and nicely clearing the upper horizontal portions 24-b, and that the outer vertical portions 24-c of the tracks 24 are tangent to the surface of the balls 28. Similar struts 23 are mounted on the bottom panel 4 and tracks 24, plates 25 with balls 28 are provided for supporting the bottom panels 19. It will be noted (Fig. 2) that the cleat 8 serves as a stop to limit the inward movement of the panels 19, and it will be understood that the cleat on the panel 5 serves the same purpose for the panels 18.

The compartments A and C are closed by a rear panel 29 extending between the side panels 2 and 3 downwardly from the top panel 1. A door 30 for the upper compartment A is mounted on the strut 23 at the front of the panel 5 by hinges 31 and provided with suitable spring detents 32 (Fig. 3).

The end panels 20 of the lateral compartments D and E are provided with rollers 33 journaled in sockets 34 counter-sunk in the bottom edges of the panels 20.

The drawer B is provided with the improved means for holding sound record discs described and claimed in my co-pending application, Serial Number 779,819, filed October 14, 1947, now Patent No. 2,593,927.

From the foregoing description of the details of construction of my improved cabinet, its use and operation will be obvious. With a selected group of records disposed in the drawer B, albums containing other groups of records, or empty albums from which the records in the drawer B have been removed can be placed in the compartment C. Additional albums can be placed in the lateral compartments D and E which can be independently adjusted to provide adequate storage space according to the number of albums to be received therein. The table provided by the top panel 1 can be used to support the record player, or, if desired, the record player can be placed on one of the tables provided by either of the panels 18, and the panel 1 may be used to support a television set, a radio set, or a lamp and ornaments. If desired, a television set can be placed on panel 1, a radio set on one panel 18 and the record player on the other panel 18.

It is obvious that the adjustability of the lateral compartments D and E makes it possible to regulate the width of the cabinet to conform most desirably with the space available in the room in which the cabinet is placed. This is a feature of very considerable value in these days of small apartments.

The improved supporting means for the lateral compartments D and E, viz. the tracks 24, balls 28 and rollers 33, insures ready and smooth lat-

eral adjustment, and the keys 22 obviate any binding tendency, to facilitate their adjustment.

Having described my invention, what I claim is:

In a cabinet, the combination of a pair of side walls, each wall having an upper horizontal slot and a lower horizontal slot; top and bottom walls connecting said side walls at their ends; a rear wall connecting said side walls at their rear edges; a front panel connecting the lower ends of the front edges of said side walls; a pair of struts mounted on said bottom wall, connecting said side walls, and disposed adjacent said rear wall and said front panel, respectively, each of said struts having a track; a shelf mounted on said struts and said front panel and connecting said side walls, said bottom wall, said struts and said shelf comprehending a compartment to which access is provided by the lower horizontal slots of the side walls; a cleat mounted between said bottom wall and said shelf midway between said side walls and connecting said struts thereby dividing said compartment into two equal portions; an intermediate panel connecting said side walls, between said top wall and said shelf and extending from said rear wall to the forward edges of said side walls, said upper horizontal slots of the side walls being disposed immediately above said intermediate panel; a pair of struts mounted on said intermediate panel, connecting said side walls and disposed adjacent said rear wall and the front edge of said intermediate panel, respectively, each of said struts on said intermediate panel having a track; a pair of laterally-movable lower shelves received through said lower horizontal slots of the side walls and provided with means adapted to support said lower shelves on the tracks on the struts on the bottom wall, for movement into and out of the two portions of said compartment, respectively; a pair of laterally-movable upper shelves received through said upper horizontal slots of the side walls and provided with means adapted to support said upper shelves on the tracks on the struts on the intermediate panel; and a pair of end walls connecting the outer ends of said lower and upper shelves.

EDWARD J. SLATTERY.
